Primary Examiner — Cathron Brooks*Assistant Examiner* — Sharon S Oum(74) *Attorney, Agent, or Firm* — Muncy, Geissler, Olds & Lowe, P.C.(57) **CLAIM**

The ornamental design for doll, as shown and described.

DESCRIPTION

FIG. 1 is a perspective view of the doll;

FIG. 2 is a front view thereof;

FIG. 3 is a rear view thereof;

FIG. 4 is a left side view thereof;

FIG. 5 is a right side view thereof;

FIG. 6 is a top plane view thereof;

FIG. 7 is a bottom plane view thereof; and,

FIG. 8 is a perspective view of the doll shown in a position of use.

The broken lines showing of the body is included for the purpose of illustrating portions of the doll and forms no part of the claimed design.

1 Claim, 8 Drawing Sheets(56)
